CUTTING MACHINE

David N. Judelshon, Park Ridge, N. J.

Application January 21, 1947, Serial No. 723,235

9 Claims. (Cl. 164—69)

1

My invention relates to a new and improved cutting machine, for cutting materials such as cloth, paper and the like.

My invention particularly relates to cutting machines of the type wherein a spirally wound roll of mass of the stock is rotated around a longitudinal spindle which is fixed to the frame, the stock being thus rotated by means of a chuck which is rotatably mounted on said spindle. In a machine of this type, a rotatable disc knife may be mounted upon a knife-head which is turnable on a shaft which connects said knife-head to a knife-carriage which is slidably mounted on longitudinal rails or other guides which are parallel to the axis of the spindle.

One object of my invention is to provide improved means for rotating the chuck; namely, by providing a speed-change mechanism for the chuck-motor.

In many cases, it is desired to cut the roll of material or a part thereof, into a plurality of slices of identical width. Another object of my invention is to provide an automatic gage, which can be manually set either into operating or non-operating position, by the use of which it will be unnecessary for the operator to make a manual adjustment of the knife-carriage for each cutting position thereof.

Other objects of my invention are stated in the following description and drawings, which illustrate a preferred embodiment thereof.

Fig. 1 is a general front view of the improved machine. The knife-carriage is shown in two respective positions, in full lines and in broken lines.

Fig. 2 is a side elevation, taken at the left of Fig. 1, showing the knife-head in its extreme non-operating position, in which the knife is at its greatest distance from the stock.

Fig. 3 is a side elevation, taken at the right of Fig. 1.

Fig. 4 is a top plan view of the machine.

Fig. 5 is an elevation, partially in section, on the line 5—5 of Fig. 4.

Fig. 6 is a section on the line 6—6 of Fig. 1.

Fig. 7 is a perspective view of the automatic gage.

Fig. 8 is a section on the line 8—8 of Fig. 7.

Fig. 9 is a detail elevation of the releasable support which is provided at one end of the spindle.

Fig. 10 is a side view of Fig. 9, partially broken away.

Fig. 5 shows a spirally wound roll or mass of cloth or other material 1, which is wound spirally

in the usual manner upon a core-sleeve 19, which is made of cardboard or other material which can be easily cut. This core-sleeve 19 is mounted turnably upon a spindle 2, which is fixed to the frame F of the machine.

Fig. 10 shows the end-portion of spindle 2 which is at the left of Fig. 1. The left-end portion is clamped releasably in the forked end of an arm 7, by means of a clamping screw 6, which preferably bears upon spindle 2 slightly above its median horizontal plane, so that spindle 2 is forced downwardly by screw 6 against its seat in arm 7. This arm 7 is pivoted at 8 to a support 9, which, as shown in Fig. 9 is releasably and adjustably fixed to the frame F of the machine by screws 10.

The arm 7 can be turned to the broken-line position of Fig. 9, in order to insert a new roll of stock or material 1, or to remove the slices or sections of said roll 1, which have been cut by the machine.

Referring to Fig. 6, and with the exception of the very short cylindrical left end-portion of said spindle 2 which is fixed to arm 7, said spindle 2 is non-cylindrical up to the point 2a of Fig. 6. Fig. 5 shows that this non-cylindrical part of spindle 2 has a planar face, 2p. The entire spindle 2 may be non-cylindrical to the left of point 2a, including the part of the spindle which is releasably clamped to arm 7. The cut is made at said planar face, while the roll 1 and its core 19 are rotated in unison, and while the disc-knife is also rotated, so that the edge of the disc-knife never touches the spindle 2.

To the right of point 2a, the spindle 2 is cylindrical, and it has a reduced cylindrical extension 2b, whose end-portion is threaded.

Adjacent to the point 2a of Fig. 6, the cylindrical part of the spindle 2 fits snugly in a washer 40 or bushing 15, which is fixed to rotatable chuck 3. Said chuck 3 and its bushing 15 rotate freely relative to spindle 2. Anti-friction bearings 16 are provided between the chuck 3 and extension 2b. A clamping nut 2c rigidly fixes the spindle 2 to the frame F of the machine.

As shown in detail in Fig. 6, the chuck 3 is provided with a drive pulley 17, whose hub is releasably fixed to said chuck 3 by means of a clamping screw 18. As shown in Fig. 1, and in greater detail in Fig. 2, the vertical plate of the chuck 3 is provided with a series of radial grooves 5, in which respective clamping dogs 4 are located. These dogs can be moved radially inwardly and outwardly until their points 4a enter the material 1, so as to rotate the roll of

material and its core 19 in unison around the axis of spindle 2. These dogs 4 are fixed in holding position by conventional means.

The chuck 3 is rotated by means of a chuck motor 20. As shown in Fig. 1, the shaft of chuck motor 20 is provided with a sprocket which is connected by means of a chain 21, to a corresponding sprocket on a shaft 22 which is mounted turnably in the frame F. This chuck-motor 21 is fixed to the frame F.

As shown in Fig. 3, a pulley 23 is fixed to shaft 22.

Fig. 4 shows a shaft 28, to which pulleys 27 and 28 are fixed. The inner faces of pulleys 27 and 28 are frusto-conical and of identical taper.

The intermediate pulley 25 has two frusto-conical faces, whose angle or taper, relative to a vertical plane, is identical with the angle or taper of said frusto-conical inner faces of pulleys 27 and 28.

The intermediate pulley 25 is slidable on shaft 28. Pulley 25 may be slidably keyed to shaft 28, or such key or other slide connection may be omitted, so that pulley 25 and shaft 28 can rotate freely relative to each other.

Pulleys 27-25 comprise a driving pulley-pair, which are driven by belt 24 and pulley 23. Pulleys 25-26 comprise a driven pulley-pair which are connected by belt 29 to pulley 17 of chuck 3. Either pair may be the driving pair or the driven pair.

The belts 24 and 29 have wedge-shaped cross-sections, as indicated in broken lines in Fig. 4, which shows one of the runs of each said belt 24 and 29. Each edge of each said belt makes the same angle with the vertical plane, as the respective frusto-conical faces of pulleys 27, 25, 26, so that each edge of each said belt makes full contact with the respective abutting frusto-conical face.

As shown in Fig. 4, shaft 28 is rotatable in bearings 30 and 31. Bearing 30 has a pivot arm 30a which is turnably mounted in frame F, and which is fixed to bearing 31 by nut 32. Bearing 31 has a hand-hold 33. As shown in Figs. 3 and 4, a toothed sector 34 is fixed to frame F. A detent-tooth 35 is connected by rod 36 to a finger-piece 37, which is pivotally connected at 38 to bearing 31.

The bearing 31 can thus be adjustably fixed to sector 34, as indicated by the full-line and broken-line positions of bearing 31 in Fig. 3.

The shaft 28 can thus be raised and lowered relative to pulleys 23 and 17.

When shaft 28 is lowered, the bottom portion of driven belt 29 is shifted towards shaft 28, thus decreasing the effective diameter of the respective pulley-pair 25-26. Due to the wedge shape of driven belt 29, this slides pulley 25 towards pulley 26, thus shifting the top portion of the driving belt 24 away from shaft 28, and increasing the effective diameter of the respective pulley-pair 25-27.

The change in relative effective diameter between pulley pairs 27-25, 25-26, thus changes the speed ratio of the drive between pulleys 23-17, so that the angular velocity of chuck 3 can be adjusted by raising and lowering shaft 28.

The sliding movement of pulley 25 on shaft 28 keeps the belts 24 and 29 taut at all times.

The disc-knife 39 is fixed to a shaft 40 which is rotatably mounted in a knife-head 41, which is pivotally connected to a knife-carriage 42, which is slidable horizontally to-and-fro in the

plane of Fig. 1, which is designated as the longitudinal plane.

Fig. 5 shows the pivot shaft 43, which pivotally connects the head 41 to the horizontally and longitudinally slidable carriage 42. The shaft 43 is freely turnable relative to head 41. The carriage 42 slides upon longitudinal guide-rails 44 which are fixed to the frame of the machine. These rails are located in longitudinal recesses of the carriage 42, so that it cannot shift transversely relative to the rails 44. The longitudinal position of the carriage 42 may be adjusted by hand. For this purpose, and as shown in Fig. 4, a hand-wheel 45 is releasably fixed to a transverse shaft 46, which is turnably mounted in the carriage 42. A gear 47 is fixed to the shaft 46. This gear 47 meshes with a companion gear which is fixed to a shaft 49 which is parallel to shaft 46 and which is also turnably mounted in the carriage 42. Sprockets 50 are fixed to shaft 49. These sprockets 50 mesh with longitudinal chains 51, whose respective ends are fixed to the frame F.

The shaft 40 of the knife 39 is provided with a sprocket which meshes with a drive-chain 52 which is shown in Figs. 1, 2, 4, and 5.

This chain 52 meshes with a sprocket which is fixed to shaft 43, so that the knife 39 is rotated by shaft 43, which operates as a countershaft.

As shown in Fig. 4, an arm 14 is fixed to carriage 42. Another arm 61 is fixed at 62 to arm 14.

As also shown in Fig. 4, one clutch-member 57 of a friction clutch is fixed to shaft 43. This shaft 43 is coaxial with a stud shaft which is connected to arm 61. A companion clutch-member 56, which is integral with sprocket 53, is slidable on said stud shaft, towards and away from the clutch-member 57.

As shown in Fig. 2, sprocket 53 is connected by a chain 54 to a sprocket which is fixed to the shaft of knife-motor 55, which is fixed to carriage 42.

As shown in Fig. 4, an arm 58, which has a handhold 59, is fixed to disc 60, which is pivoted to arm 61. The disc 60 may be concentrically or eccentrically pivoted to arm 61. When arm 58 is turned counterclockwise from its position of Fig. 4, the clutch-member 56 is slid on its stud shaft by arm 58 towards clutch member 57, thus coupling the friction clutch 56-57 and rotating shaft 43 and the disc-knife 39. The sprocket 53 may be keyed to clutch-member 56, so that clutch-member 56 is axially slidable relative to sprocket 53. When the shaft 43 is thus rotated, it does not turn the head 41. The arm 14 is provided with a stop 73, to limit the counterclockwise turning movement of arm 58. The conventional spring, not shown, may be provided to maintain the clutch-member 56 yieldingly in uncoupled position.

Said arm 58 has an extension 63 which operates a switch, not shown, in the switch box 64a, which is fixed to knife-carriage 42. When the arm 58 is in coupling position, the circuit of the grinder motor 65 is closed by the switch in switch-box 64a, so as to rotate the grinding wheel 66. When the clutch 56-57 is uncoupled, the circuit of grinder motor 65 is open. The switch in the switch box 64a which is actuated by extension 63 also automatically controls the circuit of the chuck-motor 20 and also the circuit of knife-motor 55, so that the rotation of the material or stock 1 is stopped, when the knife 39 is not rotating.

The knife head 41 is manually turned relative to shaft 43, towards and away from the stock 1,

in order to make the required series of cuts by means of the knife 39. For this purpose, and as shown in Fig. 1 and Fig. 2, a rod 67 is provided, which has a hand-hold 68. This rod 67 is fixed to the knife head 41. The knife head 41 is provided with a counterweight 69, so that it is normally biased to turn away from the stock 1. This counterweight 69 also prevents the head 41 from turning, when shaft 43 is rotated. This weight 69 is adjustably fixed to an extension 41a of the head 41. The usual knife shield 70 is also fixed to the extension 41a. As shown in Fig. 2, a single bolt 71 fixes the shield 70 and the extension 41a to the head 41. A gage 72 is fixed to an extension 67a of the arm 67.

By means of this gage, the operator can manually measure the longitudinal distance between successive cuts.

A gage is provided for manually shifting the knife-carriage 42 in a series of equal strokes, in order to cut the stock 1 into slices of equal width.

Fig. 7 shows that a gage-carriage 75 is movably associated with the knife-carriage 42. Respective and equal tension springs 76 and 76a longitudinally urge the gage-carriage 75 towards the knife-carriage 42. The ends of each said spring are respectively fixed to the carriages 42 and 75.

The rod 71 extends through a bore of gage-carriage 75. Said bore is located close to the respective end of gage-carriage 75. The diameter of the rod 71 is less than the diameter of the bore of carriage 75. As an example, if the diameter of said bore is 0.75 inch, the diameter of rod 71 is about 0.62 inch. As shown in Fig. 7, the gage-carriage 75 has a vertical recess, into which the upper edge-portion of a rail 44 extends. The gage-carriage 75 has a slightly loose sliding fit on said respective rail 44. Hence the gage-carriage 75 has a limited rocking movement around a vertical axis, relative to the respective rail 44.

A gage-nut 78 is adjustably fixed to rod 71. Said gage-nut 78 is releasably locked in its adjusted position on rod 71, by a lock nut 79. A scale 80 is fixed to knife-carriage 42, and an index or pointer 80a is fixed to gage-carriage 75.

Fig. 7 shows a part of the knife head 41, which is provided with an integral pin 84. This pin 84 abuts a rod 85 which is located in a helical spring 83. One end of said helical spring 83 is fixed to the pin 84. The other end of said helical spring 83 is fixed to the respective end of an angular rod 82. The rods 85 and 82 are not fixed to each other. There is a small space between the adjacent ends of rods 85 and 82. The rod 85 may or may not be fixed to pin 84. When the turnable head 41 is moved in the direction of the arrow 81 away from the stock 1 to its non-operative position, the pin 84 abuts the rod 85, so that rod 85 pushes rod 82, thus turning the rod 82 clockwise as indicated by the arrow 82a in Fig. 7. When the head 41 is turned towards the stock away from the rod 82, in a direction reverse to the direction of arrow 81, the tension spring 83 correspondingly turns the angular rod 82 counterclockwise. The angular rod 82 is fixed rigidly in the bore of a head or collar 86 which is turnable about a vertical axis. As shown in Fig. 8, said head or collar 86 is fixed by a set screw 87 to a vertical shaft 88, which has an integral collar 89. Fig. 8 shows the shaft 88 in its "down" or "on" position, in which said collar 89 abuts a bushing 90, which is fixed to the gage-carriage 75. Below this bushing 90, the shaft 88 is provided with respective

superposed grooves 91 and 92. At its bottom the shaft 88 is provided with a clamping eccentric 93. Below said eccentric 93, the reduced end of the shaft 88 extends below the gage-carriage 75. A stop 94 is fixed to the bottom end of the shaft 88, in order to prevent the shaft 88 from being pulled upwardly out of the gage-carriage 75. A strip of friction material 95 is fixed to the gage-carriage 75. When the eccentric 93 is in the operating or 10 clamping position shown in Fig. 8, the gage-carriage 75 is temporarily frictionally held to the respective rail 44, by the friction clamping strip 95 and eccentric 93. The eccentric 93 is turned to clamping position by pin 84 and rods 85 and 82, when knife head 41 is turned away from the stock. When knife head 41 is turned towards the stock, the tension spring 83 turns eccentric 93 to non-clamping position.

When the shaft 88 is pulled upwardly by hand 20 to its "up" position, the automatic gaging mechanism does not operate. The spring-pressed and turnable ball detent 96 then engages the lower groove 92 instead of engaging the upper groove 91, so that the eccentric 93 is held above the friction clamping strip 95.

If the operator wishes to cut the stock into a series of slices of identical width, he sets the nut 78, until the pointer 80a of the gage-carriage 75 is aligned with the corresponding scale-marking of 30 scale 80, when gage-carriage 75 abuts the nut 78, as in the position of Fig. 7. The operator then pushes the shaft 88 to its "down" position of Fig. 8.

As later described, the knife-carriage 42 is provided with automatic clamping or holding mechanism which releasably holds said knife-carriage 42 to the rails 44.

When the knife head 41 is in extreme non-operating position, which is shown in Fig. 2, the 40 knife-carriage 42 is released from the rails 44. As the knife head 41 is turned to operating position to make the respective cut, the knife-carriage 42 is clamped to rails 44, before the knife 39 touches the stock 1.

45 At the time when the knife-carriage 42 is in position for making the first cut, the gage-carriage 75 abuts the knife-carriage 42 and said gage-carriage 75 is spaced from nut 78, and the springs 76 and 76a are under tension. The operator then turns the knife head 41 towards the stock 1. He thus automatically clamps the knife-carriage 42 to the rails 44, and he then automatically closes the circuits of the knife-motor 55 and the grinder-motor 65 and the chuck-motor 20, before the 55 knife 39 touches the stock 1.

As the knife head 41 is thus turned towards the stock 1, the tension spring 83 turns the clamping eccentric 93 to the release or non-operating position, but this is immaterial, because the tension 60 springs 76 and 76a then hold the gage-carriage 75 against the temporarily fixed knife-carriage 42.

After the first cut has been made, the operator turns the knife head 41 in the direction of arrow 81, away from the stock 1. He thus automatically opens the circuits of the knife-motor 55 and of grinder motor 65 and chuck-motor 20, after the knife 39 has been moved out of contact with the stock. After the knife head 41 has been moved a short distance away from the stock, the pin 84 70 and rods 85 and 82 begin to turn the shaft 88 clockwise in the direction of arrow 82a, thus turning the clamping eccentric 93 into its clamping position. The gage-carriage 75 is thus temporarily fixed to the respective rail 44, before the 75 knife-carriage 42 is released from the rails 44.

While the knife head 41 is in the extreme non-operating position of Fig. 2, the operator slides the temporarily released knife-carriage 42 away from the temporarily fixed gage-carriage 75, until the gage-nut 78 abuts the gage-carriage 75. The gage-carriage 75 is clamped to a single face of the respective rail 44, at a point which is very close to spring 76a and which is substantially transversely spaced from spring 76. The spring 76a and rod 77 are located very close to the respective end 15f of gage-carriage 75. Hence, when the knife-carriage 42 is slid away from the temporarily fixed gage-carriage 75, the spring 76a will slightly turn the gage-carriage 75 relative to its associated rail 44, so as to bind the gage-carriage 75 upon said associated rail 44, thus ensuring a positive and reliable holding action upon the gage-carriage 75, without binding the gage-carriage 75 to the rod 77.

When the knife-carriage 42 has thus been shifted into position for making the second cut, the operator turns the knife head 41 into operating position towards the stock 1 to make the second cut, thus automatically turning rod 82 by tension spring 85 to release the gage-carriage 75 while the knife-carriage 42 remains temporarily fixed, so that the equal tension springs 76 and 76a move the gage-carriage 75 into contact with the knife-carriage 42, without binding on the rail 44. These operations are repeated, to make any desired number of cuts of equal width.

When the shaft 88 is held in its "up" position, the rod 82 is turned back and forth, without clamping the gage-carriage 75, because the eccentric 93 is held above the friction strip 95.

When the shaft 88 is thus pulled to its "up" position, the rod 82 is raised above rod 85. If desired, the rod 85 and spring 83 may be temporarily removed, if rod 85 is not fixed to pin 84.

As previously noted, I automatically clamp the knife-carriage 42 to a rail or rails 44, while the knife 39 is being moved to cutting position and the carriage 42 is held temporarily in fixed position while the respective cut is being made.

For this purpose, and as shown in Fig. 5, the knife head 41 has a bottom extension 97, in which a cylindrical roll 98 is rotatably mounted. This roll 98 has a smooth periphery. This roll 98 rides on the cam track 99 of a clamp member 100 which is pivotally connected at 101 to the knife-carriage 42. This clamp member 100 has a nut 102 adjustably fixed thereto. This nut 102 bears against a corresponding clamp member 103, which is pivoted at 104a to the knife-carriage 42. Hence, when the knife head 41 and the knife 39 are moved in unison towards the stock, the clamp member 100 is operated so that its adjustable nut 102 pushes a pin 105 which is slidable in a slide-bearing of knife-carriage 42. This pin 105 pushes a friction clamp-strip 106 which is provided in a recess of knife-carriage 42, so as to clamp the knife-carriage 42 against the respective rail 44. The companion member 103 operates similar clamping mechanism.

As shown in Fig. 5, companion stops 107 and 108 are respectively fixed to the knife head 41 and to the knife-carriage 42. The stops limit the movement of the knife head 41 and its knife 39 towards the stock. The stop 108 is adjustable.

As also shown in Fig. 5, a post 109 is fixed to the knife-carriage 42. A rod 110 is rigidly fixed to the post 109. A helical compression spring 111 is mounted upon the rod 110, and the end of the spring 111 extends slightly beyond the rod 110. When the operator turns the head 41 away from

the stock, this free part of the compression spring 111 acts as a resilient stop. Fig. 5 shows the knife head 41 in its extreme non-operating position.

Fig. 2 shows the cable C which extends from the switch box 64a to one of the terminals of the chuck-motor 20. There is a supplemental grinder 112 which removes the burr which is formed by the main grinder wheel 66. As shown in Fig. 3, this supplemental grinder 112 is mounted in a bracket 113, which is turnably connected at 114 to carriage 42.

As shown in Fig. 2, the grinder motor 65 is mounted on a block 115 which is adjustable in a direction perpendicular to the plane of Fig. 2, relative to the block 116. The block 115 is thus adjusted, relative to the block 116, by rotating the hand wheel 117 which operates a conventional adjusting screw. The block 116 is adjustable in a direction parallel to the plane of Fig. 2, relative to the block 118, this adjustment being made by the hand wheel 119 which operates a conventional adjusting screw.

The block 118 is turnable around a vertical axis relative to the knife-carriage 42.

This mounting of the grinder motor permits accurate adjustment of the grinder wheel 66.

Fig. 1 shows a switch box 120, which has a conventional reversing switch for reversing the direction of rotation of the chuck-motor 20. This reversing switch, not shown, is operated by handle 121.

I have described a preferred embodiment of my invention, but numerous changes, omissions and additions can be made without departing from its scope.

Thus, the knife motor 55 can be controlled by an ordinary switch, so that the operation of the knife motor 55 is independent of the position of the knife head 41 relative to the stock.

Numerous other modifications are included within the scope of the invention. In this embodiment, the mass of stock is a spirally wound roll, but the machine can operate upon any mass of material. The gage-carriage 75 may also be designated as a stop-carriage, because it stops the sliding movement of the knife-carriage 42.

I claim:

1. In a cutting machine of the type which has a frame and in which a rotating mass of stock is cut by a knife, a straight spindle for rotatably supporting said mass of stock, said spindle being fixed to said frame, a chuck which is rotatably mounted on said spindle, said chuck having means for engaging and rotating said mass, a driven pulley fixed to said chuck, a driven pulley mounted on a drive shaft, a countershaft which is located in a bearing which is pivotally connected to said frame by a pivot member which is located below said countershaft, said driven pulley being located above said countershaft and said countershaft being located above said driven pulley, said countershaft having two outer pulleys fixed thereto and having an intermediate pulley slidable thereon, said three pulleys having adjacent frustoconical faces which have the same angle, a drive belt which connects said drive pulley to one of said outer pulleys and to said intermediate pulley, a driven belt which connects said driven pulley to the other of said outer pulleys and to said intermediate pulley, said belts having wedge-shaped cross-sections and having side faces which contact with the respective frustoconical faces of said pulleys on said countershaft
2. A cutting machine of the type in which a

rotating mass of stock is cut by a knife, said machine having a frame, supporting means for supporting said mass to rotate relative to said frame around a selected axis, mass-rotating means adapted to rotate said mass relative to said frame around said selected axis, a knife-carriage, guide means for guiding said knife-carriage to move in a direction parallel to said selected axis, a rotatable shaft mounted in said knife-carriage, the axis of said rotatable shaft being parallel to said selected axis, a knife head pivoted on said rotatable shaft, said rotatable shaft being freely rotatable relative to said knife head, a clutch member fixed to said rotatable shaft, a supplemental shaft mounted on said knife-carriage and aligned with said rotatable shaft, a supplemental clutch member mounted on said supplemental shaft and slidable on said supplemental shaft to slide towards and away from said first-mentioned clutch-member, manually operated control means for coupling said clutch-members, a disc-knife fixed to a knife-shaft which is mounted in said knife head, a knife-motor fixed to said knife carriage and connected by respective connecting means to said supplemental clutch member, said rotatable shaft being connected by respective connecting means to said knife shaft.

3. A cutting machine according to claim 2, said machine having a mass-rotating motor for operating said mass rotating means, a grinder-motor connected to said knife head, a grinder-wheel operated by said grinder-motor, and switch-means for controlling the circuit of said grinder-motor and said mass-rotating motor, and means operated by said manually operated control means for operating said switch means to close said circuits while said knife head is moved in unison with said knife to operating cutting position and to open said circuits while said knife head is moved in unison with said knife to non-operating non-cutting position.

4. A cutting machine which has a frame, a knife-carriage which is movable to-and-fro relative to said frame in a selected path, a knife head pivoted to said knife-carriage, a knife mounted on said knife head, holding means movably connected to said knife-carriage and adapted releasably to hold said knife-carriage to said frame when said holding means are in operating position, said holding means being movable to a non-operating position to release said knife-carriage from said frame, said holding means being operatively connected to said knife head, said knife head moving said holding means to operating position when said knife head is moved towards cutting position; guide means for guiding said knife-carriage to move in said selected path.

5. A cutting machine which has a frame and a support for the material which is to be cut, a knife-carriage which is movable to-and-fro relative to said frame in a selected path, knife-carriage guide means for guiding said knife-carriage to move in said selected path, a knife head pivoted to said knife-carriage, a knife mounted in said knife head, a gage-carriage slidable on respective gage-carriage guide-means relative to said frame in said selected path and also slidable towards and away from said knife-carriage in said selected path, a stop fixed to said knife-carriage, said stop being located to abut said gage-carriage to limit the movement of said knife-carriage away from said gage-carriage,

and gage-carriage holding-means for holding said gage-carriage releasably fixed to said frame.

6. A cutting machine according to claim 5, in which said gage-carriage holding means are operatively connected to said knife head to be moved into holding position when said knife head is moved away from said support and to be moved into release position when said knife head is moved towards said support.

10 7. A cutting machine according to claim 5, in which said gage-carriage holding means are operatively connected to said knife head to be moved into holding position when said knife is moved away from said support and to be moved into release position when said knife head is moved towards said support, said machine also having knife-carriage holding means for holding said knife-carriage releasably to said frame, said knife-carriage holding means being operatively connected to said knife head to be moved into holding position when said knife head is moved towards said support and to be moved into release position when said knife head is moved away from said support.

15 25 8. A cutting machine according to claim 5, in which said gage-carriage holding means are operatively connected to said knife head to be moved into holding position when said knife head is moved away from said support and to be moved into release position when said knife head is moved towards said support, said machine also having knife-carriage holding means for holding said knife-carriage releasably to said frame, said knife-carriage holding means being operatively connected to said knife head to be moved into holding position when said knife head is moved towards said support and to be moved into release position when said knife head is moved away from said support, and spring means urging said gage-carriage towards said knife-carriage.

30 35 9. A cutting machine according to claim 5, in which said gage-carriage holding means are operatively connected to said knife head to be moved into holding position when said knife head is moved away from said support and to be moved into release position when said knife head is moved towards said support, said gage-carriage guide-means being a single guide-member which is located and which fits loosely in an upstanding recess of said gage-carriage, said gage carriage having a limited turning movement around a vertical axis relative to said single guide-member, said gage-carriage holding means being friction means which are located and operative at only a single face of said recess, and a tension spring which is connected to said gage-carriage and to said knife-carriage, said tension spring being transversely spaced from said face of said recess to produce said limited turning movement when said gage-carriage holding means are in holding position and said knife-carriage is moved away from said gage-carriage.

65 DAVID N. JUDELSHON.
